Images of applicator guns believed to be available before the priority date of Jun. 1, 2021.

(Primary Examiner — Philip S Hyder

(74) *Attorney, Agent, or Firm* — Renner, Otto, Boisselle & Sklar, LLP(57) **CLAIM**

The ornamental design for an applicator gun, as shown and described.

DESCRIPTION

FIG. 1 is a top, right, rear perspective view of an applicator gun showing my new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken line showing is for the purpose of illustrating portions of the applicator gun and forms no part of the claimed design.

1 Claim, 5 Drawing Sheets(56)
